NEEDLE HOLDER

Howard E. Marick and Elmer Schweitzer, Philadelphia, Pa.

Application November 6, 1939, Serial No. 303,028

9 Claims. (Cl. 223—109)

This invention relates to needle holders which are designed for association with thread carrying spools and is concerned primarily with the provision of an improved needle holder having novel characteristics to which important advantages attach.

A needle holder of the type with which this invention is concerned ordinarily is assembled in the bore of a thread carrying spool, and it is highly desirable that the holder be firmly positioned in the bore and yet be readily removable therefrom. Accordingly an important object of the invention lies in the provision of a holder which is so designed as to accomplish this purpose.

In carrying out this objective the invention contemplates the provision of a holder that is substantially semi-cylindrical for a portion of its length, and substantially fully cylindrical for the remaining portion. The fully cylindrical part is defined by a split sleeve construction which permits of a certain amount of contraction and subsequent expansion thereof. Thus the split sleeve construction may be slightly compressed as it is inserted in the bore of a spool, and due to the resiliency of the sheet metal from which the holder is made subsequent expansion will cause the split sleeve construction to engage the bore of the spool and maintain the holder in position therein.

Moreover the full cylindrical formation provides adequate structure for maintaining the needles in position in the holder, while the semi-cylindrical formation permits of the withdrawal of the needles therefrom when their use is required.

Obviously a needle holder of the structure above outlined must be formed with a closure at each end. The end of the holder which is designed for insertion into the bore of the spool carries a tab which is of substantially the same shape as a cross section of the cylindrical part of the holder, and when this tab is bent up into the proper position it serves to close the holder at that end.

An important object of the invention lies in the provision of a novel type construction at the end carrying the semi-cylindrical formation. In accordance with this invention this tab takes the form of a tongue which is bent into position substantially normal to the axis of the holder. In the first instance this tongue constitutes a closure at that end for the holder. The tongue is appropriately dimensioned so that it projects beyond the peripheral edge of the spool end when the holder is positioned therein. It is thereby constituted a means for preventing accidental and

undesirable rolling of the spool. This dimensioning of the tongue also lends to the latter the ability of functioning as a handle which may be engaged by the user to remove the holder from the spool bore sufficiently to render the needles carried therein available.

This tongue also acts as a stop to limit the extent to which the holder may be inserted into the spool bore, thereby providing assurance that the holder is accurately positioned in a bore in a desirable manner.

Another important object of the invention is the provision of a needle holder of the character above noted in which the tongue at one end is formed with an aperture through which the thread which is carried by the spool is adapted to pass. When the thread extends through this aperture the positioning of the holder in the bore to full insertion causes the tongue to clamp the thread between the tongue and the spool end, thus guarding against the accidental unwinding of the thread from the spool.

A further object of the invention is the provision of a needle holder of the character above noted in which one side of the tongue carries thread cutting means in the form of a notch which is preferably located conveniently adjacent to the aperture through which the thread passes. Thus when the user of the spool with the holder assembled therein is desirous of cutting off a length of thread the latter may be inserted in the notch and cut off in an obvious manner.

A spool holder embodying the above noted structural characteristics is readily adapted to being made by first stamping a blank of appropriate shape from sheet metal and then folding and bending the blank into the ultimate formation. Thus the cost of manufacturing the holders is held at an extremely low minimum, this being an important feature of the invention.

Various other more detailed objects and advantages of the invention will in part become apparent, and in part be hereinafter stated, as the description of the invention proceeds.

The invention, therefore, comprises a needle holder that is designed for assembly in the bore of a thread carrying spool, and which holder consists of a blank of sheet metal that is bent into a formation providing a substantially fully cylindrical split sleeve construction and a substantially semi-cylindrical formation which are adapted for insertion in the spool bore, the split sleeve construction constituting a means for maintaining the holder in position in the bore. A tab at one end closes the split sleeve, while a tongue closes the

semi-cylindrical end and projects beyond the peripheral edge of the spool end when the holder is inserted in the spool bore. This tongue is formed with an aperture, and the side edge thereof carries a thread cutting notch.

For a full and more complete understanding of the invention reference may be had to the following description and accompanying drawing, wherein

10 Figure 1 is a side view developing a thread carrying spool in section with the holder of this invention positioned therein and shown in elevation,

15 Figure 2 is a top plan view of the assembly shown in Figure 1,

Figure 3 is a plan view of a blank of sheet metal prior to being folded and bent into the ultimate formation, and

20 Figure 4 is a detailed perspective view of the finally fashioned holder.

Referring now to the drawing, wherein like reference characters denote corresponding parts, a spool of conventional design is shown in Figure 1 and referred to in its entirety by the reference character S. The spool S consists of spool ends 10 and 11, and extending therebetween is the hub portion of the spool 12 formed with a bore 13. A length of thread is wound on the hub portion 12 in a well-known manner, and is identified by the reference character 14.

30 The improved holder of this invention is designed for insertion into the bore 13. This holder is referred to in its entirety by the reference character H, and is shown in detail in Figure 4.

35 The holder comprises a substantially fully cylindrical part 15 that is rendered of a split sleeve construction by the split at 16. This split sleeve construction 15 is closed at one end by the end closure designated 17. Communicating with the other end of the split sleeve construction 15 is a cut away part or substantially semi-cylindrical portion 18, the end of the latter being closed by a tongue designated 19. This tongue 19 is formed with an aperture 20 and one side edge thereof

45 carries a notch 21.

Referring now to Figure 3 it will be noted that a blank which is identified by the reference character B may be stamped from a piece of sheet metal, and this blank B is adapted to be bent and folded into the final holder formation depicted in Figure 4. This blank B includes a tab 17 at one end, which, in the final construction, is the end closure 17. At the other end the blank includes the tongue 19 which is, of course, the corresponding part of the final form. Adjacent the tongue 19 is a substantially rectangular part 18a which is bent into the substantially cylindrical formation 18, while adjacent the tab 17 is the rectangular part 15a which is wider than the part 18a. Thus when the parts 18a and 15a are bent (preferably over a suitable mandrel) they assume the formation shown in Figure 4 providing the cut-away part 18 and the split sleeve construction 15.

65 Referring now to Figures 1 and 2, it will be noted that one or more needles such as represented at 22 may be positioned in the holder and are maintained therein by the fully cylindrical formation 15. When the holder is assembled 70 with the spool the tongue 19 engages the spool end 10, as illustrated. Thus the tongue acts as a stop limiting the extent to which the holder may be inserted in the bore 13. Prior to insertion of the holder H into the bore 13 the split sleeve construction 15 will be slightly compressed

so that the subsequent effect of the tendency to expand will cause the split sleeve construction to engage the bore 13 and maintain the holder in position.

It will be noted that the extremity of the 5 tongue 19 projects beyond the peripheral edge of the spool end 10 and thus is rendered available as a handle which may be grasped by a user when it is desired to withdraw the holder H from the bore to render the needles 22 available. This 10 projecting portion of the tongue 19 also prevents the spool from accidentally rolling about.

As shown more clearly in Figure 2, the thread 14 is passed through the aperture 20. Thus when the tongue 19 engages the spool end 10, as shown 15 in Figures 1 and 2, accidental unwinding of the thread 14 is also inhibited. It is also notable that the notch 21 is conveniently adjacent to the aperture 20. Thus when the user is desirous of cutting off a length of thread the latter is inserted 20 in the notch 21, and upon appropriate pressure being applied the desired severing will be accomplished. The tongue 19 may also be employed as a means for preventing accidental unwinding of the thread even though the latter does not pass 25 through the aperture 20. The thread 14 may merely be clamped between the spool end 10 and tongue 19.

30 An important advantage of the above described holder is that when assembled with the spool it is 30 substantially fully received in the bore. Thus the length of the spool is not materially increased. In fact, the only increase in the dimension of the spool is the projecting tongue, which is desirable, as above pointed out.

35 While a preferred specific embodiment of the invention is hereinbefore set forth it is to be clearly understood that the invention is not to be limited to the exact construction illustrated and described, because various modifications of 40 these details may be provided in putting the invention into practice within the purview of the appended claims.

We claim:

1. In combination, a thread carrying spool 45 comprising spool ends connected by a hub portion formed with a bore that extends throughout the entire length of the spool, and a needle holder positioned in said bore, said needle holder consisting of a substantially fully cylindrical part 50 and a cutaway part, an end closure for the fully cylindrical part and a tongue closing the end of the cutaway part, said tongue engaging one of the spool ends and projecting beyond the peripheral edge thereof.

2. In combination, a thread carrying spool comprising spool ends connected by a hub portion formed with a bore that extends throughout the entire length of the spool, and a needle holder 60 positioned in said bore, said needle holder consisting of a split sleeve construction and a cutaway part both of which are positioned in the said bore, a closure for the split sleeve construction and a tongue at the end of the cutaway part closing the same and projecting beyond the peripheral edge of a spool end.

3. In combination, a thread carrying spool comprising spool ends connected by a hub portion formed with a bore that extends throughout the entire length of the spool, and a needle holder 70 positioned in said bore, said needle holder consisting of a split sleeve construction and a cutaway part both of which are positioned in said bore, a closure for the split sleeve construction and a tongue at the end of the cutaway part 75

closing the same and projecting beyond the peripheral edge of a spool end, said tongue being formed with an aperture through which the thread carried by the spool is adapted to pass.

5. 4. In combination, a thread carrying spool comprising spool ends connected by a hub portion formed with a bore that extends throughout the entire length of the spool, and a needle holder positioned in said bore, said needle holder consisting of a substantially fully cylindrical part and a cutaway part, an end closure for the fully cylindrical part and a tongue closing the end of the cutaway part, said tongue engaging one of the spool ends and projecting beyond the peripheral edge thereof, said tongue being formed with an aperture through which the thread carried by the spool is adapted to pass, and thread cutting means carried by one edge of said tongue.

5. A thread holder of the character described comprising a single piece of sheet metal that is bent into a formation providing a split sleeve construction, and a cutaway part immediately adjacent thereto, a tab closing one end of the split sleeve construction and a tongue substantially normal to the axis of the split sleeve construction and cutaway part and which tongue closes the end of said cutaway part, said tongue being adapted to project beyond the edge of the end of a spool with which the holder is assembled.

30. 6. A thread holder of the character described comprising a single piece of sheet metal that is bent into a formation providing a split sleeve construction, and a cutaway part immediately adjacent thereto, a tab closing one end of the split sleeve construction and a tongue substantially normal to the axis of the split sleeve construction and cutaway part, said tongue being formed

with an aperture through which a thread is adapted to pass.

7. A thread holder of the character described comprising a single piece of sheet metal that is bent into a formation providing a split sleeve construction, and a substantially semi-cylindrical part immediately adjacent thereto, a tab closing one end of the split sleeve construction and a tongue substantially normal to the axis of the split sleeve construction and semi-cylindrical part and which tongue closes the end of said semi-cylindrical part, one edge of said tongue carrying thread cutting means.

8. A thread holder of the character described comprising a single piece of sheet metal that is bent into a formation providing a split sleeve construction, and a substantially semi-cylindrical part immediately adjacent thereto, a tab closing one end of the split sleeve construction and a tongue substantially normal to the axis of the split sleeve construction and semi-cylindrical part and which tongue closes the end of said semi-cylindrical part, said tongue being formed with an aperture while an edge of the tongue is formed with a thread cutting notch.

9. A thread holder of the character described comprising a single piece of form sustaining material that is formed into a shape providing a split sleeve construction, and a substantially semi-cylindrical part immediately adjacent thereto, a tab closing one end of said split sleeve construction, and a tongue substantially normal to the axis of said split sleeve construction and semi-cylindrical part and arranged to close one end of said semi-cylindrical part.
